(57) **CLAIM**

We claim the ornamental design for a model vehicle brushless motor, as shown and described.

DESCRIPTION

FIG. 1 is an upper, left, front perspective view of a model vehicle brushless motor showing our new design;

FIG. 2 is a front elevation view thereof;

FIG. 3 is a rear elevation view thereof;

FIG. 4 is an upper plan view thereof;

FIG. 5 is a lower plan view thereof;

FIG. 6 is a right side elevation view thereof;

FIG. 7 is a left side elevation view thereof;

FIG. 8 is an upper, right, rear perspective view thereof; and, FIG. 9 is a lower, right, rear perspective view of the model vehicle brushless motor.

In the drawings, the broken lines illustrate portions of the model vehicle brushless motor that form no part of the claimed design.
